UNITED STATES PATENT OFFICE.

FOKKO BRANDT, OF KANSAS CITY, KANSAS.

STUMP-EXTRACTING MACHINE.

Application filed March 8, 1920. Serial No. 364,094.

To all whom it may concern:

Be it known that I, FOKKO BRANDT, a citizen of the Republic of Germany, and resident of Kansas City, county of Wyandotte, State of Kansas, have invented a certain new and useful Improvement in Stump-Extracting Machines, of which the following is a complete specification.

This invention relates to tractor stump pulling machines and has for its object to produce a machine of this character by which the largest stump can be readily extracted. A further object is to produce a machine of this character provided with equipment for pulling small stumps and for lifting them from the ground if necessary and for dragging them to any point desired.

More specifically, my object is to produce a machine having a hydraulic lift which will exert tremendous lifting power, and in addition thereto other hydraulic lifts provided with levers whereby the auxiliary lifts shall be capable of performing their work expeditiously and exerting a pulling or lifting strain over a greater range of movement than would otherwise be possible.

A still further object of the invention is to provide a tractor in which the motor operates a pump for the operation of the hydraulic lift, and means also operated by the motor for effecting the swinging of the main lift to an inclined position to enable the machine to pass under low bridges and the like. Another object is to provide the machine with winding drums also actuated from the motor, for the purpose of drawing a stump, log or other object up to the machine when the latter is stationary.

With these general objects in view and others of a secondary character as will hereinafter appear, the invention consists in certain novel and useful features of construction and combinations of parts as herein-after described and claimed; and in order that it may be fully understood, reference is to be had to the accompanying drawings, in which—

Figure 1 is a top plan view of a tractor stump pulling machine embodying the invention;

Figure 2 is a side elevation of the machine;

Figure 3 is a rear elevation of the machine;

Figure 4 is a vertical section taken on the line IV—IV, of Figure 1;

Figure 5 is a vertical section taken on the line V—V of Figure 4;

Figure 6 is an enlarged horizontal section taken on the line VI—VI of Figure 5;

Figure 7 is a central vertical section through the steering drum and adjacent parts of the machine; and

Figure 8 is a diagrammatic plan view of the machine.

Referring to the drawings where similar reference characters identify corresponding parts in all of the figures, 1 and 2 indicate the inner and outer side rails of the machine frames, the rear end of the adjacent rails 1 and 2 being connected by plates 3. The front end of said rails are connected by front rails 4, the latter projecting inwardly beyond the inner rails and being connected to the rear end of forwardly projecting rails 5 which in turn are connected at their front end by a front rail 6. The rails 4 and 5 are braced by inclined rails 7. At the rear end of the machine a cross brace 8 connects rails 1.

The frame is made portable by mounting it upon a rolling support of the type shown or any other suitable type, which affords a substantial or extended bearing contact with the ground, particularly when the same is soft, to avoid embedment therein when subjected to tremendous downward pressure incidental to the extraction of large tree stumps or the lifting of heavy weights, and it is also desirable that such rolling support shall be susceptible of being driven by a motor on the frame. The frame is provided with bearings 14 for alined cross shafts 15, for service as herein-after mentioned.

The hydraulic lift mechanism is constructed as follows: 51 indicates a pair of cylinders standing over the spaces between companion rails 1 and 2, and connected by cross-bars 52, at their upper ends. Fitting slidingly in the cylinders 51 are hollow pistons 53 provided at their ends with caps 54 from which project upwardly standards 55. Rigid standards 56 are also mounted on said

2
 caps at opposite sides of standards 55, and standards 56 are connected together by horizontal channel beams 60. The said standards 55 and 56 carry rearwardly projecting pins 57 from which are suspended tubes 58 provided with internal collars 59 at their lower ends. (See Figure 4.) The standards 56 are connected by cross beams 60 so that both pistons shall move upwardly and 10 downwardly together. The cross beams 60 are connected together at suitable points by blocks 61, and suspended from said blocks are chains 61^a adapted to be fastened in any suitable or preferred manner to the tree 15 stump to be pulled or to any other object it is desirous to lift by means of the hydraulic lift.

Each cylinder 51 is closed at its bottom as at 62 and provided with depending arms 20 63 pivotally engaging the adjacent shaft 15 between the hangers 14, so that the lift may be swung downward to the inclined position shown by Figure 2, as hereinafter explained. It will be noticed by reference to Figure 5 25 that one of the arms 63 of the corresponding cylinder 51 is provided with an opening 64 for the reception of a locking pin 65 provided at its outer end with a handle 66. Said pin engages an opening 67 in the adjacent rail 30 2 of the frame, and is limited in its inward movement by the engagement of the handle 66 with the outer end of a cylinder 68 secured to said rail 2, it being noted by reference to Figure 6 that the outer end of the 35 cylinder 68 is provided with notches 68^a wherein the handle may fit when turned a quarter revolution. Each pin is provided near its inner end with an enlargement 69, and a spring 70 encircles the stem and bears 40 against said enlargement and the outer end of the cylinder and therefore tends to force said pin inwardly into engagement with the opening 64 of the depending arm of cylinder 51. When the machine is performing service 45 the locking pin will be in the position shown by Figure 6 so as to oppose any tendency of the lift to swing forward or rearward. When it is desired to lower the lift for travel upon the roadway, the pins 66 will be drawn 50 outward to disengage them from the arm 63, and then turned at right angles to such position so that they shall engage the outer ends of cylinders 68 and thus be held from re-engagement with the said openings. Each 55 piston 53 is closed by a head 71 at its lower end provided with a cup leather 72 of common type, and near the lower end of each cylinder 51 is provided a port 73 controlled by a yieldingly closed valve 74 connected to a rock lever 75 fulcrumed on and between a pair of lugs 76 depending from the bottom of the said cylinder 51, the opposite end of said lever being connected to the lower end of a rod 77 extending up into the tube 58 60 and being provided within said tube with a

head 77^a, the function of which will hereinafter appear. The cylinder chambers below the pistons are connected to water supply pipes 78 connected at their front ends to a valve controlled discharge pipe 79 of a 70 pump mechanism 80 mounted upon and adapted to receive liquid from a tank 81 suitably secured in the front portion of the frame of the machine. Return pipes 78^a 75 connect the ports 73 with the tank. The pumping mechanism includes a pulley 82 engaged by a drive belt 83 leading from a pulley 84 journaled on the transverse driving shaft 85 of the machine, said shaft being suitably connected to the engine shaft hereinafter mentioned. The engine or motor 86 is mounted on the front end of the machine and upon said tank and is adapted as hereinafter explained to not only propel the machine but also to effect movement of 85 all the operative parts thereof. A hand clutch 87 of conventional type is arranged to make the pulley 84 fast to the driving shaft when it is desired to drive the pump or any other machinery, it being noted that 90 a belt for the operation of other machinery can be readily led from the pulley 84 because the same occupies a position in a lower plane than the pump pulley 82.

As thus far described it will be apparent 95 that when the pump is in operation, water can be forced through pipes 78 and against the cup washer 72 and thereby raise the pistons, and when the latter have attained their upward limit of movement the collars 59 of tubes 58, strike the heads or enlargements 77^a of rods 77, and thus rock the levers 75 and unseat the valves 74. As this occurs water supplied by the pump to the lower end of the cylinders, passes off through ports 100 73 and pipes 78 to the tank, leaving the pistons elevated at the points attained when the tripping of the valves occurred, but incapable of being raised to a higher plane 105 by the pump. By the control of the valve 79, the lifting action of the lift can be arrested immediately at any desired point, and to lower the pistons, the water is permitted to flow back from the cylinders 110 through the pump to the tank. 115

To tilt the lift to the position indicated by dotted line and to return it to upright position, the following mechanism is provided. 88 are bearing brackets mounted upon the rails 1 and 2 and journaled upon 120 and between said brackets are grooved sheaves 89. A transverse shaft 90 is journaled in brackets 91 mounted upon rails 1 and 2 near their front end, and secured upon said shaft 90 are double ended drums 125 92. Around each drum a cable 93 is wound a number of times, one end of each cable being attached to lugs 94 mounted on the cylinders 51. The other ends of said cables engage the sheaves 89 and then extend up 130

to and are attached to the same lugs. The cables thus form in side view triangular figures, the front portions of the cables tending to brace the lift against rearward swinging movement, and the rear portions of the cables tending to prevent forward swinging movement of the said lift, it being understood that these cables are preferably of metal so that they shall be capable of maintaining the lift in a vertical position under any ordinary service required of them. When the shaft 90 is stationary, it will be apparent that the rear portions of said cables will guard as effectively against forward swinging movement of the lift as if they were rigidly attached to the latter, this being due to the fact that the lift tends to swing in a plane intersecting that on which said portions of the cables will swing. The same statement applies of course with respect to the front portions of said cables. In very heavy work the locking pins 66 may also be employed to assist the cables in holding the lift in vertical position, especially if the lift exerted is not exactly vertical as will frequently occur due to failure to stop the machine with the transverse beams or cross bars 52 squarely over the stump or the object to be lifted.

It may frequently happen that the main lifting mechanism described is incapable of lifting a stump completely out of the ground due to the fact that the root thereof may be of considerable length, especially trees having tap roots. In this event the auxiliary lifting mechanisms will be found useful, as they can be connected to the loosened trunk and exert sufficient lifting power to completely dislodge the roots, or while they are attached to the stump the machine may be driven and thus drag the stump laterally and complete its uprooting. These auxiliary lifting devices are designed admirably for more quickly uprooting small stumps than is possible by means of the main lifting mechanism so that the work of extracting stumps may be facilitated by the use of the small lifting devices instead of the large one. As will hereinafter appear each of these small or auxiliary lifting devices may extract a small stump simultaneously, or both may be coupled to the same stump for the purpose of extracting the same. Referring particularly to Figure 4, it will be seen that a bearing bracket 95 is swiveled in each bracket 3 at the rear end of the machine, each bracket 95 being equipped with a cylinder 96, and pivoted to each cylinder is a lifting lever 98 equipped at its outer or free end with a grappling hook 99. Each cylinder 96, like cylinders 51, is provided at its lower end with a closed bottom having a port 100 normally controlled by a yieldingly closed valve 101 connected to a rock lever 102. A drain or discharge port for the cyl-

inder is indicated at 105, and a supply pipe 103, the latter pipe being connected to valve controlled branch pipes 104 leading from the valve controlled pipes 79 between the valve of the latter and the pump. The drain pipe 105 leads to the tank 81, as shown clearly in Figure 8, which figure it will be noted is diagrammatic for a clearer showing of the arrangement of the water pipes, it being understood that said pipes in practice will be suitably secured in the channels of the frame bars of the machine.

106 are hollow pistons mounted in the cylinders 96 and provided at their lower ends with cup washers 107 and at their upper ends with rigid yokes 108 within which are journaled grooved sheaves 109, the shaft of the sheaves being extended to form support for depending tubes 111 having internal collars 112 at their lower ends. Rods 113 extend slidably through said collars and are provided with heads 114 at their upper ends and are pivotally connected at their lower ends to the rock levers 102. From the foregoing it will be apparent that when the proper valves are open, water will enter the cylinders 96 and force the pistons 106 upward until the collars 112 of tubes 111, strike the head 114 and thus through the connections described unseat the valves 101. When this occurs the upward movement of the pistons is arrested, as the water from the pump passes through ports 101 and pipes 103 to the tank, and when it is desired to lower the pistons, the water is permitted to flow back from the cylinder through the pump to the tank.

Cables 115 are fitted over the sheaves 109. At their ends they are secured as at 116 to the rear or bifurcated ends of the levers 98, extending through grooves in said ends which are curved as indicated at 117. Between the sheaves 109 and said levers, the cables are looped under and engage guide sheaves 118 mounted on the cylinders 96. By this arrangement it will be apparent that when the pistons are moved upward, the levers are rocked upward at their outer ends.

Connecting each beam 1 at its front end with the inner ends of the adjacent frame beams 4 and 5, are aligned housings 119 for the differential shaft members 120, geared to the driving shaft 85 by mechanism common in motor car and motor truck construction and therefore not detailed. To operate the shaft 90, it is provided with a worm gear (not shown) in a housing 123 and said gear is engaged by a worm (not shown) on a shaft 124 geared in any suitable manner to the drive shaft 85. It will be understood that the mechanism for transmitting power from the drive shaft 85 to the differential shafts 120 is illustrative only, and that it is not necessary to detail it as it is conventional in motor car construction, and the same

statement applies to the means for transmitting power from the drive shaft to shaft 90.

While I have illustrated and described what I now regard as the preferred form of construction, I desire to reserve the right to make such changes or modifications as may fairly fall within the scope of the following claims.

10 I claim:

1. A tractor stump pulling machine, comprising a wheeled frame open between its sides, a pair of opposite vertical extensible lifts pivotally mounted on the sides of the frame, a cross-bar connecting the lifts rigidly together above the frame, lifting tackle suspended from the cross-bar between the lifts, rotatable guides mounted on the sides of the frame forward and rearward of the lifts, cables engaging the rotatable guides at corresponding sides of the frame and converging upwardly therefrom and attached at their extremities to the respective lifts, and means to operate the cables to swing the lifts to an inclined position and back to a vertical position.

2. A tractor stump pulling machine, comprising a wheeled frame open between its sides, a pair of opposite vertical extensible lifts pivotally mounted on the sides of the frame, a cross-bar connecting the lifts, tackle mechanism suspended from the cross-bar between the lifts, rotatable guides mounted on the sides of the frame forward and rearward of the lifts, cables engaging the rotatable guides at corresponding sides of the frame and converging upwardly therefrom and attached at their extremities to the respective lifts, means to operate cables to swing the lifts to an inclined position and back to a vertical position, and means to lock the lifts in vertical or operative position.

3. A tractor stump pulling machine, comprising a wheeled frame, a lift pivoted thereon, sets of winding drums and sheaves at opposite sides of the pivotal point of the lift, cables attached at their ends to the lift and each engaging one of the drums and sheaves and means actuated by the motor of the tractor for revolving the drum to tilt the lift or move it from a tilted to an upright position.

4. A tractor stump pulling machine comprising a frame, a pair of vertical lifts pivotally mounted on the frame, a cross-bar rigidly connecting the lifts, tackle mechanisms suspended from the cross-bar, rotary guides at opposite sides of the vertical plane of the pivotal points of the lifts, cables engaging the guides and extending convergingly upward and attached at their upper ends to the lifts at points nearer to the pivotal points of the latter when vertical, than to the guides, to constitute checks against accidental pivotal movement to the lifts,

and means to impart travel to the cables to tilt the lifts or return them from a tilted to upright position.

5. A tractor stump pulling machine comprising a frame, a pair of vertical lifts pivotally mounted on the frame, a cross-bar rigidly connecting the lifts, tackle mechanism suspended from the cross-bar, rotary guides at opposite sides of the vertical plane of the pivotal points of the lifts, cables engaging the guides and extending convergingly upward and attached at their upper ends to the lifts at points nearer to the pivotal points of the latter when vertical, than to the guides, to constitute checks against accidental pivotal movement of the lifts, means to impart travel to the cables to tilt the lifts or return them from a tilted to upright position, and auxiliary means to lock the lifts rigid to the frame.

6. In a tractor stump pulling machine, a pair of rigidly connected cylinders secured to the respective sides of the frame of the machine, and provided with water inlets and drain ports, yieldingly closed valves for the drain ports, pistons fitting in and connected together above the cylinders, lifting tackle suspended from the connection of and between the pistons, means to force liquid through the inlet ports into the cylinders, and means actuated by upward movement of the pistons, for unseating said valves for retaining the pistons in elevated position.

7. In a tractor stump pulling machine, a pair of rigidly connected cylinders secured to the respective sides of the frame of the machine and provided with water inlet and drain ports, yieldingly closed valves for the drain ports, pistons fitting in and connected together above the cylinders, lifting tackle suspended from the connection of the pistons, a tank, and pumping mechanism operated by the motor of the tractor, to force liquid from the tank through said inlet port into the lower end of the cylinders to raise the pistons.

8. In a tractor stump pulling machine, a pair of rigidly connected cylinders, secured to the respective sides of the frame of the machine and provided with water inlet and drain ports, yieldingly closed valves for the drain ports, pistons fitting in and connected together above the cylinders, lifting tackle suspended from the connection between the pistons, a tank, pumping mechanism operated by the motor of the tractor, to force liquid from the tank through said inlet ports into the lower end of the cylinders to raise the pistons, and means actuated by upward movement of the pistons, to unseat said valves for retaining the pistons in elevated position.

In witness whereof I hereto affix my signature.

FOKKO BRANDT.
